1

This invention relates to a balanced ultra-high-frequency oscillation generator tunable over a wide range of operating frequencies.

Oscillation generators designed for operation in the ultra-high-frequency range usually comprise an oscillator tube and a frequency-determining circuit provided by an effectively resonant transmission line coupled between the anode and control electrodes of the oscillator tube. A tuning device, such as a short-circuiting member, is included in the line and arranged to be adjustable along the conductors thereof for the purpose of tuning the generator over a prescribed range of operating frequencies. A source of space current is applied to the anode electrode of the oscillator tube through one of the conductors of the line, being isolated from the control electrode thereof by means of a suitable blocking condenser which is generally incorporated in the short-circuiting member.

The operating frequency range of such a generator is determined by the allowable travel of the short-circuiting member, the highest obtainable frequency being realized when this member is advanced along the line as far as possible in the direction of the oscillator tube. The value of this highest obtainable frequency is determined by the distributed parameters of the line and the anode-control electrode capacitance of the oscillator tube which constitutes a loading effect at the electrode terminals of the line. Where a wide operating frequency range is desired, the oscillation generator may also be provided with a second effectively resonant transmission line which is coupled to the oscillator tube and tunable in the manner described. In this case, the lines are tuned together and an increased range of operating frequencies results since the loading effect for each line contributed by the interelectrode capacitance of the oscillator tube is approximately one-half that of the single-line arrangement. Such oscillation generators, since they include a single oscillator tube, are capable of delivering but a limited amount of power. Additionally, it is difficult to construct blocking condensers which have suitable electrical characteristics at ultra-high frequencies and can withstand high voltages. These limitations may render the described arrangements unsuited for certain applications.

Other prior art oscillation generators for use in the ultra-high-frequency range comprise a pair of oscillator tubes connected in a push-pull circuit and having a first effectively resonant transmission line coupled between their anode

2

electrodes and a second effectively resonant transmission line coupled between their control electrodes. The lines include short-circuiting members for tuning which are such that the generator is of the tuned-plate tuned-grid type. While these arrangements provide an increased power output as compared with that of the single-tube oscillation generators mentioned above, they have a limited range of operating frequencies due to the loading effect contributed to the electrode-terminal portions of the transmission lines by the interelectrode capacitance of the oscillator tubes. Furthermore, in view of the tuning difficulties presented, it has not been considered expedient to double the line arrangement in order to reduce this loading effect, thereby to increase the operating frequency range of such generators.

It is an object of the invention, therefore, to provide an improved balanced ultra-high-frequency oscillation generator which is tunable over a predetermined range of operating frequencies and which avoids one or more of the above-mentioned limitations of prior art arrangements.

It is another object of the invention to provide an improved balanced ultra-high-frequency oscillation generator which is tunable over a relatively wide range of operating frequencies.

It is still a further object of the invention to provide a balanced ultra-high-frequency oscillation generator tunable over a predetermined range of operating frequencies and having an improved stability characteristic.

In accordance with the invention, a balanced ultra-high-frequency oscillation generator tunable over a predetermined range of operating frequencies comprises a pair of vacuum tubes individually having anode and control electrodes. The generator includes a first balanced transmission line comprising a pair of open conductors individually directly coupled to corresponding electrodes of the vacuum tubes and including adjustable tuning means which constitute therewith a frequency-adjusting circuit for tuning the generator over the aforesaid range of operating frequencies. The generator further includes a second balanced transmission line comprising a pair of conductors individually directly coupled to the other corresponding electrodes of the vacuum tubes and extending therefrom in the same direction as the first-mentioned line. The second line has a resonant frequency outside of the range of operating frequencies of the generator and is electrically coupled to the first line for substantially all adjustments of the tuning means

for transferring energy from the first to the second line to sustain oscillations.

In the specific application of the invention to be described hereinafter, a balanced ultra-high-frequency oscillation generator including a frequency-determining circuit and a pair of vacuum tubes individually having anode, cathode and control electrodes comprises a pair of short-circuited transmission lines. Each of the lines has an effective electrical length substantially equal to an integral multiple of a quarter-wave length at a predetermined operating frequency of the generator and each line comprises a pair of open conductors individually coupled to corresponding electrodes of the vacuum tubes. The frequency-determining circuit has at the aforementioned operating frequency a desired mode of resonance in which the currents in corresponding portions of the conductors of each of the lines are in phase opposition and the lines are included in an additional circuit which has an undesired mode of resonance in which the currents in corresponding portions of the conductors are in phase. The generator includes means for so loading the last-named circuit that the undesired mode of resonance occurs at a predetermined frequency substantially different from the aforementioned operating frequency of the generator.

For a better understanding of the present invention, together with other and further objects thereof, reference is had to the following description taken in connection with the accompanying drawing, and its scope will be pointed out in the appended claims.

In the drawing, Fig. 1 is a schematic circuit diagram of a balanced ultra-high-frequency oscillation generator embodying the present invention; Fig. 2 is a schematic circuit diagram which is electrically equivalent to the circuit of Fig. 1; Figs. 3a and 3b are additional schematic circuit diagrams utilized in describing an operating characteristic of the Fig. 1 arrangement; while Fig. 4 comprises a graph representing the power output-frequency characteristic of the oscillation generator represented in Fig. 1.

Referring now more particularly to Fig. 1 of the drawing, there is represented a balanced ultra-high-frequency oscillation generator tunable over a prescribed wide range of operating frequencies and embodying the present invention. The generator includes a pair of vacuum tubes 10 and 11 individually having anode, cathode and control electrodes. The generator also includes a first plurality of balanced transmission lines individually directly coupled to corresponding electrodes of each of the vacuum tubes. Specifically, one transmission line comprising a pair of open parallel conductors 12, 13 is directly coupled to the anode electrodes of tubes 10 and 11, respectively, while another transmission line comprising a pair of open parallel conductors 14, 15 is similarly coupled to the anode electrodes of the vacuum tubes. The conductors of each such line have uniformly distributed inductance and capacitance and the lines are symmetrically disposed with reference to the vacuum tubes, extending therefrom in opposite directions, as represented in the drawing. This relationship of lines 12, 13 and 14, 15 may be described as a feed-through arrangement since conductors 14 and 15 may be considered effectively to comprise extensions of conductors 12 and 13, respectively. Adjustable short-circuiting elements 16 and 17 are included, respectively, in lines 12, 13 and 14, 15 and are arranged to

be adjustable along the conductors thereof. These short-circuiting elements comprise adjustable tuning means and, in conjunction with their associated transmission lines, constitute a frequency-adjusting circuit for tuning the generator over a prescribed wide range of operating frequencies.

The generator further includes a second plurality of balanced transmission lines corresponding in number with the first-described plurality and individually directly coupled to other corresponding electrodes of tubes 10, 11. In particular, one transmission line comprising a pair of open conductors 18, 19 is directly coupled to the control electrodes of the vacuum tubes, while another transmission line comprising a pair of open conductors 20, 21 is similarly coupled to the control electrodes of the tubes. The conductors of lines 18, 19 and 20, 21 have uniformly distributed inductance and capacitance and their physical arrangement with reference to tubes 10 and 11 is substantially the same as that described in connection with lines 12, 13 and 14, 15. In other words, as represented in the drawing, corresponding ones of the described first and second plurality of lines extend from the tubes in the same direction. Each of lines 18, 19 and 20, 21 is proportioned to have an effective electrical length equal to an integral multiple of a quarter-wave length at a predetermined operating frequency outside of, and preferably above, the range of operating frequencies of the generator. That is to say, each such line has a resonant frequency which lies above the range of operating frequencies of the generator. This proportioning of the electrical lengths of lines 18, 19 and 20, 21, as well as their physical relationship with reference to lines 12, 13 and 14, 15, is effective electrically to couple corresponding ones of the first and second pluralities of lines for substantially all adjustments of the tuning means 16, 17 for transferring energy from the first to the second plurality of lines in order to sustain oscillations. As an aid to this coupling, line 18, 19 includes an inverted or reversed loop portion 22 which is magnetically coupled to short-circuiting element 16 of line 12, 13 for substantially all adjustments of the short-circuiting element, while line 20, 21 includes a reversed loop portion 23 magnetically coupled to short-circuiting element 17 of line 14, 15. These loop portions are inverted so that the energy transferred between the lines has the proper polarity for sustaining oscillations.

The cathodes of tubes 10 and 11 are of the directly-heated type and have a pair of cathode leads which connect to a source of heater voltage, as indicated by the arrows. The mid-point of the cathode of tube 10 is coupled to ground through a radio-frequency choke 30. Condensers 31 and 32 are provided to maintain substantially the same radio-frequency potential at both cathode leads. Radio-frequency chokes 33 and 34 and condensers 35 and 36 provide a filter circuit for isolating radio-frequency signal voltages from the source of heater voltage. The cathode circuit of tube 11 is substantially identical with that of tube 10 and corresponding components thereof are identified by like reference numerals primed.

A source of space current, indicated +B, is coupled to the anode electrodes of tubes 10 and 11 through a radio-frequency choke 40 and the conductors of transmission line 12, 13. The control electrodes of the vacuum tubes are grounded

through a radio-frequency choke 41 and a grid resistor 42. An adjustable condenser 43 is coupled between the short-circuited terminals of transmission line 14, 15 and ground for a purpose to be described fully hereinafter. An output signal is obtained from the generator by means of a pick-up loop 50 which is electrically coupled to transmission line 14, 15. This output signal may be supplied to a suitable utilizing circuit, such as an antenna system 51, by way of a coaxial cable 52 which couples the antenna to pick-up loop 50. The antenna circuit is tunable through an adjustable condenser 53.

In considering the operation of the described arrangement, it will be understood that short-circuiting elements 16 and 17 are adjusted to have substantially identical positions with reference to their associated transmission lines. For any given adjustment of these short-circuiting elements, transmission lines 12, 13 and 14, 15 individually comprise an effectively resonant transmission line having an effective electrical length which is preferably equal to a quarter-wave length corresponding to a predetermined operating frequency of the oscillation generator. As is well known from transmission-line theory, any effectively resonant transmission line having such an effective electrical length exhibits the impedance characteristics of a parallel resonant circuit. Therefore, each short-circuiting element with its associated transmission line provides a frequency-adjusting circuit for the generator, the frequency-adjusting circuit provided by each such line and its short-circuiting element having the same operating or resonant frequency. The particular value of this operating frequency is determined by: (1) the position of the short-circuiting element which determines the effective electrical length of the line; (2) the distributed parameters of the line; and (3) the terminating impedance of the line which, for the case under consideration, comprises substantially one-half the interelectrode capacitance of the anode and cathode electrodes of vacuum tubes 10 and 11 since lines 12, 13 and 14, 15 are arranged in a parallel relationship with reference to these electrodes. Additionally, for any given adjustment of the short-circuiting elements 16 and 17, transmission lines 18, 19 and 20, 21 have a resonant frequency which is above the operating frequency of the generator. For this reason, lines 18, 19 and 20, 21 effectively comprise inductive reactances which are electrically coupled to lines 12, 13 and 14, 15 to provide the requisite feed-back voltage for sustaining oscillations. The coupling between these lines utilized for transferring feed-back energy is contributed largely by the loop portions 22 and 23 since these loop portions are magnetically coupled with the short-circuiting elements of transmission lines 12, 13 and 14, 15 where there is a current maximum under stabilized oscillating conditions.

From the foregoing discussion it will be evident that the schematic circuit diagram of Fig. 2 is the electrical equivalent of the Fig. 1 arrangement. In this equivalent circuit the distributed inductance of transmission lines 12, 13 and 14, 15 is represented by the lumped inductance L, while the distributed capacitance thereof and the anode-cathode interelectrode capacitance of tubes 10 and 11 are represented by the lumped capacitance C. Transmission lines 18, 19 and 20, 21, which have been described as presenting an inductive reactance for any given adjustment of the short-circuiting elements 16 and 17, are repre-

sented by the inductance L_1 having a mutual coupling M with the inductance L. The circuit arrangement of Fig. 2 will be recognized as a conventional push-pull type oscillation generator, the operation of which is well understood in the art so that a description thereof is unnecessary. For tuning the oscillation generator over its range of operating frequencies, the inductance and capacitance of its frequency-adjusting circuit are simultaneously adjustable, as indicated in Fig. 2, through short-circuiting elements 16 and 17 which are effective, respectively, to adjust the effective electrical lengths of transmission lines 12, 13 and 14, 15 to integral multiples of a quarter-wave length corresponding to a desired operating frequency.

While a balanced oscillation generator of the type under consideration has satisfactory stability characteristics when constructed of lumped parameters, an unstable operating condition is possible when the generator employs transmission lines arranged in a feed-through manner, as represented in Fig. 1. This unstable operating condition may be attributed to a parasitic mode of resonance of the transmission lines which comprise the frequency-adjusting circuit of the generator and will be described with particular reference to the sketches of Figs. 3a and 3b.

The diagram of Fig. 3a represents the frequency-adjusting circuit of the generator provided by the short-circuited effectively resonant transmission lines 12, 13 and 14, 15 for a particular operating condition. This circuit is represented as having, at the particular operating frequency of the generator, a desired mode of resonance in which voltage maxima occur at the anode electrodes, as represented by the polarity indications, and in which current maxima occur at the short-circuited terminals of each transmission line. The current distribution along the lines is such that the current in corresponding portions of the conductors of each line is in phase opposition. This current relationship is indicated by the arrows. In this, the desired mode of resonance, the frequency-adjusting circuit has an axis of electrical symmetry which corresponds to that of the generator and the resonant frequency varies with adjustments of short-circuiting elements 16 and 17.

The condition represented in Fig. 3b is an undesired or parasitic mode of resonance in which voltage maxima occur at the short-circuited terminals of the transmission lines, while the current maxima occur at the anode electrodes of the vacuum tubes. The current distribution along the lines is such that the currents in corresponding portions of the conductors of each line are in phase. For this mode of resonance the circuit is symmetrical about an axis which is perpendicular to the axis of electrical symmetry of the generator. When this undesired mode of resonance occurs, conductors 12 and 14 are effectively in parallel with conductors 13 and 15 in a circuit which is completed through ground by way of the condensers C', shown in broken-line construction since they comprise the inherent capacitance to ground at the short-circuited terminals of the transmission lines. It may be shown to a first approximation that the frequency of this undesired mode of resonance is independent of the position of short-circuiting elements 16 and 17.

Where the desired and the undesired mode of resonance appear at the same operating frequency of the generator, the power output is seriously

reduced because the circuit exhibiting the undesired mode of resonance acts as a load on the generator and absorbs a large portion of the power. In accordance with the invention, condenser 43 is coupled to transmission line 14, 15 for the purpose of so loading the circuit arrangement represented by the diagram of Fig. 3b that the undesired mode of resonance occurs at a predetermined frequency which is substantially different from any desired operating frequency of the generator. The frequency-adjusting circuit has a voltage minima at the short-circuited terminals of the transmission lines so that coupling the loading condenser 43 at this point has substantially no effect on the operating frequency of the frequency-adjusting circuit.

The power output-frequency characteristic of the oscillation generator of Fig. 1 is represented by the full-line curve of Fig. 4. In this figure, the frequency designations f_1 and f_2 represent the lower and upper limits, respectively, of the desired operating frequency range of the oscillation generator. Over this range the power output has a substantially constant value. The loading effect of condenser 43 causes the reduced power output, resulting from the aforescribed undesired mode resonance, to occur at a frequency f_4 outside of the desired range. In absence of this loading feature, a reduced power output may occur at some frequency f_3 within the desired operating frequency range.

A balanced ultra-high frequency oscillation generator in accordance with the present invention will be seen to have a relatively wide range of operating frequencies by virtue of the feed-through line arrangement utilized as the frequency-adjusting circuit. Furthermore, the arrangement is characterized by an improved stability and produces a substantially constant power output at all operating frequencies within the desired wide range.

Where an unusually wide operating range is not required, it will be apparent that a single balanced transmission line may be coupled to the anode electrodes of tubes 10 and 11 and a single balanced transmission line may likewise be coupled to the control electrodes thereof. In any case, the transmission lines may have any of a variety of shapes. It is only necessary that the lines be so shaped and arranged that there is an electrical coupling between the lines connected to the anode electrodes and those connected to the control electrodes of the vacuum tubes for the purpose of providing a voltage feed-back path.

Oscillation generators constructed in accordance with the invention and arranged for operation at very high frequencies may include transmission lines of relatively short physical lengths. In particular, lines 18, 19 and 20, 21 have progressively shorter physical lengths for higher operating frequencies of the generator. In the extreme case, these lines have the physical appearance of a single-turn inductor and, in such a case, the inductor leads may be considered to comprise the open conductors of a transmission line. Furthermore, while lines 18, 19 and 20, 21 include reversed-loop portions in the described preferred embodiment, it will be understood that the invention is not limited to such a line structure. As an alternative arrangement, lines 18, 19 and 20, 21 may consist of well-known short-circuited lines. In this alternative form of the invention, the described effective electrical length of these lines with reference to that of lines 12, 13 and 14, 15,

as well as the described geometrical relationship of such lines, affords sufficient feedback to sustain oscillations.

It will be understood that the loading reactance, consisting of condenser 43, may be distributed and applied to the short-circuited terminals of each of transmission lines 12, 13 and 14, 15 instead of being coupled to a single line in the manner represented in Fig. 1.

- 10 While there have been described what are at present considered to be the preferred embodiments of this invention, it will be obvious to those skilled in the art that various changes and modifications may be made therein without departing 15 from the invention, and it is, therefore, aimed in the appended claims to cover all such changes and modifications as fall within the true spirit and scope of the invention.

What is claimed is:

- 20 1. A balanced ultra-high-frequency oscillation generation tunable over a predetermined range of operating frequencies comprising, a pair of vacuum tubes individually having anode and control electrodes, a first balanced transmission line 25 comprising a pair of open conductors individually directly coupled to correspondence electrodes of said tubes, adjustable tuning means included in said line and constituting therewith a frequency-adjusting circuit for tuning said generator over 30 said range of operating frequencies, and a second balanced transmission line comprising a pair of conductors individually directly coupled to the other corresponding electrodes of said tubes and extending therefrom in the same direction as said 35 first line, said second line having a resonant frequency outside of said range of operating frequencies and being electrically coupled to said first line for substantially all adjustments of said tuning means for transferring energy from said 40 first to said second line to sustain oscillations.

2. A balanced ultra-high-frequency oscillation generator tunable over a predetermined range of operating frequencies comprising, a pair of vacuum tubes individually having anode and control electrodes, a first balanced transmission line comprising a pair of open parallel conductors individually directly coupled to corresponding electrodes of said tubes, adjustable tuning means included in said line and constituting therewith a frequency-adjusting circuit for tuning said generator over said range of operating frequencies, and a second balanced transmission line comprising a pair of conductors individually 55 directly coupled to the other corresponding electrodes of said tubes and extending therefrom in the same direction as said first line, said second line having a resonant frequency outside of said range of operating frequencies and being electrically coupled to said first line for substantially all adjustments of said tuning means for transferring energy from said first to said second line to sustain oscillations.

3. A balanced ultra-high-frequency oscillation 60 generator tunable over a predetermined range of operating frequencies comprising, a pair of vacuum tubes individually having anode and control electrodes, a first balanced transmission line comprising a pair of open conductors individually 65 directly coupled to said anode electrodes of said tubes, adjustable tuning means included in said line and constituting therewith a frequency-adjusting circuit for tuning said generator over said range of operating frequencies, and a second balanced transmission line comprising a pair of

conductors individually directly coupled to said control electrodes of said tubes and extending therefrom in the same direction as said first line, said second line having a resonant frequency outside of said range of operating frequencies and being electrically coupled to said first line for substantially all adjustments of said tuning means for transferring energy from said first to said second line to sustain oscillations.

4. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable short-circuiting means included in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having a resonant frequency outside of said range of operating frequencies and being electrically coupled to said first line for substantially all adjustments of said short-circuiting means for transferring energy from said first to said second line to sustain oscillations.

5. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable tuning means included in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having an effective electrical length equal to an integral multiple of a quarter-wave length at a predetermined frequency outside of said range of operating frequencies and being electrically coupled to said first line for substantially all adjustments of said tuning means for transferring energy from said first to said second line to sustain oscillations.

6. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable tuning means included in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having an effective electrical length equal to an integral multiple of a quarter-wave length at a predetermined frequency above said range of operating frequencies and being electrically coupled to said first line for substantially all adjustments of said tuning

means for transferring energy from said first to said second line to sustain oscillations.

7. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable tuning means included in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having a resonant frequency outside of said range of operating frequencies and including a loop portion which is electrically coupled to said first line for substantially all adjustments of said tuning means for transferring energy from said first to said second line to sustain oscillations.

8. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable short-circuiting means included in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having a resonant frequency outside of said range of operating frequencies and including a loop portion which is magnetically coupled to said short-circuiting means for substantially all adjustments thereof for transferring energy from said first to said second line to sustain oscillations.

9. A balanced ultra-high-frequency oscillation generator tunable over a predetermined range of operating frequencies comprising, a pair of vacuum tubes individually having anode and control electrodes, a first balanced transmission line comprising a pair of open conductors individually directly coupled to corresponding electrodes of said tubes, adjustable tuning means including in said line and constituting therewith a frequency-adjusting circuit for tuning said generator over said range of operating frequencies, and a second balanced transmission line comprising a pair of conductors individually directly coupled to the other corresponding electrodes of said tubes and extending therefrom in the same direction as said first line, said second line having a resonant frequency outside of said range of operating frequencies and including a reversed loop portion which is electrically coupled to said first line for substantially all adjustments of said tuning means for transferring energy from said first to said second line to sustain oscillations.

10. A balanced ultra-high-frequency oscillation generator tunable over a predetermined range of operating frequencies comprising, a pair of vacuum tubes individually having anode and control electrodes, a first plurality of balanced transmission lines each comprising a pair of open conductors individually directly coupled to cor-

11

responding electrodes of said tubes, adjustable tuning means included in said first plurality of lines and constituting therewith a frequency-adjusting circuit for tuning said generator over said range of operating frequencies, and a second plurality of balanced transmission lines corresponding in number with said first-named plurality and each extending therefrom in the same direction as a corresponding one of said first-named plurality of lines and each comprising a pair of conductors individually directly coupled to the other corresponding electrodes of said tubes, said second plurality of lines individually having a resonant frequency outside of said range of operating frequencies and being electrically coupled to a corresponding one of said first plurality of lines for substantially all adjustments of said tuning means for transferring energy from said first to said second plurality of lines to sustain oscillations.

11. A balanced ultra-high-frequency oscillation generator tunable over a predetermined range of operating frequencies comprising, a pair of vacuum tubes individually having anode and control electrodes, a first pair of balanced transmission lines each comprising a pair of open conductors individually directly coupled to corresponding electrodes of said tubes, adjustable tuning means included in said first pair of lines and constituting therewith a frequency-adjusting circuit for tuning said generator over said range of

5
10
15

12

operating frequencies, and a second pair of balanced transmission lines each comprising a pair of conductors individually directly coupled to the other corresponding electrodes of said tubes and each extending therefrom in the same direction as respective ones of said first-named pair of lines, said second pair of lines individually having a resonant frequency outside of said range of operating frequencies and each being electrically coupled to a corresponding one of said first pair of lines for substantially all adjustments of said tuning means for transferring energy from said first to said second pair of lines to sustain oscillations.
